CLAIM

The ornamental design for the sleeve for loading bulk viscous material from a container into a dispensing device, as shown and described.

DESCRIPTION

FIG. 1 is an isometric view of a sleeve for loading bulk viscous material from a container into a dispensing device in accordance with my design;

FIG. 2 is a front view of the sleeve for loading bulk viscous material from a container into a dispensing device of FIG. 1, the left side view and the right side view being identical; FIG. 3 is a top view of the sleeve for loading bulk viscous material from a container into a dispensing device of FIG. 1; FIG. 4 is a bottom view of the sleeve for loading bulk viscous material from a container into a dispensing device of FIG. 1; and,

FIG. 5 is a cross-sectional view of the sleeve for loading bulk viscous material from a container into a dispensing device of FIG. 1, taken along lines 5-5 of FIG. 1.

The broken-line disclosure is understood to represent environmental subject matter in which the claimed design is embodied, but which forms no part of the claimed design.

1 Claim, 5 Drawing Sheets
